UNITED STATES PATENT OFFICE.

GEORGE W. DOXSIE, OF HARING, MICHIGAN, ASSIGNOR TO HIMSELF, AND
EPHRAIM SHAY, OF SAME PLACE.

LOGGING-WHEEL.

SPECIFICATION forming part of Letters Patent No. 273,043, dated February 27, 1883.

Application filed December 4, 1882. (No model.)

To all whom it may concern:

Be it known that I, GEORGE W. DOXSIE, of Haring, in the county of Wexford and State of Michigan, have invented a new and useful 5 Improvement in Logging-Wheels, of which the following is a full, clear, and exact description.

My invention relates to the logging-wheels employed for suspending logs from the axle, 10 between the wheels, to carry them, the logs being loaded by raising up the tongue nearly to the perpendicular and using it for a lever by hitching the team to the end of the tongue with a long chain, to raise up the logs by an 15 eccentric hitch of the suspending-chains upon the axle; and it consists of a lever contrivance for raising the tongue preparatory to the employment of it as a lever to raise the logs.

The invention also consists of a seat attachment for the driver, and also of a guard attachment to the wheels to prevent the spokes from being chafed and broken by the chains which suspend the logs from the axle, which sometimes swing against them by the thrusts 25 of logs on uneven roads, all as hereinafter fully described.

Reference is to be had to the accompanying drawings, forming part of this specification, in which similar letters of reference indicate corresponding parts in all the figures.

Figure 1 is a transverse section of the axle, taken on the line *xx* of Fig. 2, and side elevation of one of the wheels, showing the improvements of my invention. Fig. 2 is a rear elevation of the axle, the wheels being broken off through the hubs. Fig. 3 is a transverse section of the axle and side elevation of the tongue and the seat attachment, the seat being folded over on the tongue, as when not required for use; and Fig. 4 is a section of the axle, showing the lever attachment for elevating the tongue.

a represents the axle, *b* the tongue, and *c* the wheels on which the logs are to be carried, the logs being loaded by raising up the tongue nearly to a perpendicular position, so that the chains *d* will swing down and hitch under the logs, and the logs will be raised off the ground by swinging the tongue down again to the working position, which is done by hitching a team to the upper end of the tongue by a long chain and drawing it down by the team.

In a large machine for drawing heavy logs it is sometimes difficult for one man to raise 55 the tongue and also hitch the chains under the logs. I therefore propose to employ a lever, *e*, for this purpose, and contrive for the application of it near one of the wheels, where the attendant requires to stand to fasten the chains 60 *d* under the log; and for this purpose I propose to provide the lever with a metal point, *f*, fastened by a band, *g*, to insert in a socket in the axle, and will also use a chain, *h*, for bracing the lever, the chain being passed 65 around the axle and fastened thereto by studs *j*, to prevent it from slipping, and the ends of the chain being fastened to a band, *i*, attached to the lever a suitable distance above the axle. For the seat I propose to suspend 70 a short board, *k*, from eye-studs *l* at the top and back edge of the axle by a bail, *m*, to which the board is secured by a staple, *n*, a suitable distance from the end of the board, to enable the latter to project under the axle, as represented in Figs. 1 and 2, for being suspended 75 on the bail in the rearward extension represented, suitably for affording a convenient seat for the driver.

When the seat is not required for use it may 80 be swung up over the axle and tongue, where it may be fastened by a hook and chain, *u*, to a staple, *o*, of the tongue. To prevent the spokes of the wheels from being damaged by the chains *d*, which are frequently swung aside 85 by the thrusts of the logs suspended in them against the spokes, I apply one or more guard rings or bands, *p*, to the inner sides of the spokes, as shown in Fig. 1.

Having thus described my invention, what I 90 claim as new, and desire to secure by Letters Patent, is—

1. The combination of the lever *e* and chain-brace *h* with the axle *a* of a pair of logging-wheels, said lever being located with respect 95 to chains *d* substantially as described.

2. The combination of seat *k*, eye-studs *l*, and bail *m* with the axle *a*, said seat being connected to said bail suitably for extending under the axle and being supported on the bail, 100 substantially as described.

GEORGE W. DOXSIE.
